US00D923681S

(12) **United States Design Patent** (10) Patent No.: **US D923,681 S**
Lee et al. (45) Date of Patent: **** Jun. 29, 2021**

(54) **INTERACTIVE PERSONAL ROBOT FOR HOME USE**

(71) Applicant: **LG ELECTRONICS INC.**, Seoul (KR)

(72) Inventors: **Younghwan Lee**, Seoul (KR); **Hophil Lee**, Seoul (KR); **Jaebeom Im**, Seoul (KR); **Seungwoo Maeng**, Seoul (KR)

(73) Assignee: **LG ELECTRONICS INC.**, Seoul (KR)

(**) Term: **15 Years**

(21) Appl. No.: **35/509,280**

(22) Filed: **Jun. 20, 2019**

(80) **Hague Agreement Data**

Int. Filing Date: **Jun. 20, 2019**

Int. Reg. No.: **DM/207550**

Int. Reg. Date: **Jun. 20, 2019**

Int. Reg. Pub. Date: **May 8, 2020**

(30) **Foreign Application Priority Data**

Jan. 30, 2019 (KR) 30-2019-0004695

(51) **LOC (13) Cl.** **15-99**

(52) **U.S. Cl.**

USPC **D15/199**

CPC **G05D 1/024** (2013.01)

(58) **Field of Classification Search**

USPC D15/199; D21/578-583, 621, 622

(57) **CLAIM**

The ornamental design for an interactive personal robot for home use, as shown and described.

DESCRIPTION

1. Interactive personal robot for home use

1.1 : Perspective

1.2 : Front

1.3 : Back

1.4 : Right

1.5 : Left

1.6 : Top

1.7 : Bottom

1.8 : Reference view showing the state of use

1.9 : Reference view showing the state of use

The parts shown by means of broken lines in the reproductions are not part of the claimed design.

1 Claim, 9 Drawing Sheets
